UNITED STATES PATENT OFFICE.

ZEPHIREN DUCHEMAIN, OF HAVERHILL, MASSACHUSETTS.

DESIGN FOR A GARMENT-HANGER.

SPECIFICATION forming part of Design No. 25,715, dated June 30, 1896.

Application filed March 31, 1896. Serial No. 585,668. Term of patent 7 years.

To all whom it may concern:

Be it known that I, ZEPHIREN DUCHEMAIN, of Haverhill, in the county of Essex and State of Massachusetts, have invented and produced a new and original Design for a Garment-Hanger, of which the following is a full, clear, and exact description.

Reference is to be had to the accompanying drawing, which represents a perspective view 10 of a garment-hanger embodying my new design.

The hanger comprises the wire-skeleton top presenting the two oppositely-projecting horizontal members *a b*, the sides of which have 15 downward extensions *c*, two of which are joined by a cross-piece *d*, having a downwardly-turned upper end *d'*, the forwardly-extending member *e*, that is composed of two arms forming continuations of the extensions 20 *c*, the said arms being return-bent, as at *e'*; the vertical skeleton shank *f*, the two members of

which are continuations of the forwardly-extending member *e*, and the hook-like termination *g*, which ranges upward and outward in front of the shank *f*, and the members of 25 which hook have rearward bends *g'*, which are joined to the shank *f* by downwardly and inwardly curved bends *g''*, that cross at the bottom of the hanger, as shown.

The leading feature of my design resides in 30 the hanger having the horizontal top, the forward extension below said top, the vertical shank extending downward below said forward extension, and the upwardly-ranging hook-like termination in front of said shank. 35

I claim—

The design for a garment-hanger herein shown and described.

ZEPHIREN DUCHEMAIN.
